UNITED STATES PATENT OFFICE.

CHARLES H. CROWELL, OF BROOKLYN, NEW YORK.

MANUAL TAPE-MOISTENING MACHINE.

1,276,728.

Specification of Letters Patent. Patented Aug. 27, 1918.

Application filed November 10, 1916. Serial No. 130,506.

To all whom it may concern:

Be it known that I, CHARLES H. CROWELL, a citizen of the United States, and resident of Brooklyn, county of Kings, city and State of New York, have made a certain new and useful Invention Relating to Manual Tape-Moistening Machines, of which the following is a specification, taken in connection with the accompanying drawing, which forms part of the same.

This invention relates especially to light portable moistening machines which can preferably be folded for transportation and in which a sealed tape container may be inserted and held so as to preserve the tape against undesirable atmospheric influences while it is being used in the moistener. The moistener may comprise a feed plate mounted on the frame so that the tape end may be conveniently engaged and fed forward over the moistener into such position that its free forward end may be readily engaged by the operator and drawn forward to the desired extent. Then the tape can be drawn upward against a stationary type cutter mounted adjacent the feed plate, for instance, so as to sever the tape length and preferably simultaneously lock the rest of the tape against forward movement. A moistener of the belt type, for instance, may be reversibly mounted in the moistening tank so that it may be withdrawn and reversed in position to assist in freeing it from accumulated gum, etc., from time to time, and the belt moistener of felt or other material is preferably mounted on a distributing carrier block having capillary slots so as to draw up the water and supply it freely to the moistener adjacent its acting moistening surface.

In the accompanying drawings showing in a somewhat diagrammatic way an illustrative embodiment of this invention,

Figure 1 is a vertical section taken substantially along the line 1—1 of Fig. 2.

Fig. 2 is a plan view.

Fig. 3 is an enlarged partial sectional view taken along the line 3—3 of Fig. 1.

Fig. 4 is an enlarged transverse section through the moistener taken along the line 4—4 of Fig. 1.

Fig. 5 is a perspective view of the distributing moistener carrier block.

Fig. 6 is a top view of the machine with the tape container and moistener removed,

the tank being shown in section along the line 6—6 of Fig. 7; and

Fig. 7 is a sectional elevation through the machine, the vertical guide plate being swung down into shipping position.

The frame of the machine may, if desired, comprise a frame base 30 of cast iron or other suitable material which is preferably provided with the integral moistening tank 28, the rear part of which may be provided with a cover 21, if desired. The rear part of the base is arranged to support a roll of tape which may, if desired, be mounted within a tape container or cardboard box or case 1 which is preferably supported in suitable adjustable side clamps or members 35 adjustably mounted on the frame base in any suitable way. As indicated in Figs. 2 and 3 these side clamps may be formed with suitable clamping flanges 31, 32 which may, if desired, extend upward still farther at the forward ends so as to form projections 33, 34 at this point to more effectively guide the edge of the container. These clamps may be adjustably mounted on the base as by providing them with adjusting slots 36 with which adjusting screws 37 coöperate so as to allow a considerable range of lateral adjustment to accommodate tape containers of different width and effectively hold the clamps in holding position to firmly support any container which may thus be laterally centered on the base.

The container may be in the form of a paper or cardboard box 1 which as indicated may be provided with a tape aperture 8 with which a suitable closing flap 9 may coöperate so as to normally close this aperture and prevent moisture injuring the tape while still allowing the tape 11 to be withdrawn from time to time as it is used. The tape roll 4 may be revolvably mounted within the box on the usual core 75 which may rotate on the support pin 5 held in position within the container as by the pins or fastening members 6 driven in through the sides of the container. If desired, the stationary or revoluble guide 7 may be mounted within the container adjacent the tape aperture 8 so as to guide the tape at this point and it is of course understood that these parts are assembled and the closing flap secured as by the wire staple 10, and then the entire container sealed as by running the strip of

sealing tape 2 around its edges so as to securely close the joint 3 between the edge flaps of the container and render the tape package resistant to the deleterious action 5 of moist air, etc., which has an especially undesirable action with the hygroscopic gum coatings which are most desirable on gum tape where quick and thorough moistening and strong adhesion are desired. The user 10 may slip this sealed container, the sides of which may of course contain suitable advertising matter, into the moistening machine in the same condition in which the container and tape are sold and shipped and 15 then may continue to withdraw the tape 11 through the substantially closed tape aperture, so that all of the tape on the roll can be used without opening the container or giving undesirable access to moist air, etc. 20 In order to more effectively guide the tape 11 to the moistening and severing devices a vertical guide plate 12 may be provided to coöperate with the front edge of the container and guides, such as 14, 16, may be 25 provided adjacent the corner 15 of this guide plate so that the tape threaded through these guides may be kept in proper lateral alinement during its use. Suitable stiffening ribs such as 13, may be formed in this 30 guide plate as shown in Figs. 1 and 3 and for convenience of shipping this guide plate may be movably mounted though preferably permanently secured to the frame as by pivoting the same thereto. The brackets 17 on 35 this plate may coöperate with the pin, 18 secured in similar brackets 38 on the frame so that this guide plate may either be swung up into vertical position, as shown in Fig. 1 so as to coöperate with a tape container, 40 or for convenience of packing and shipping the guide plate may be swung down as shown in Fig. 7, so that it is of substantially the same height as the moistening tank and other parts of the machine. 45 For some purposes it is desirable to form a feed plate to facilitate the manual withdrawal of the tape from the machine and this may be formed on the cover 22 of the moistening tank which may be smoothly 50 finished or preferably provided with a brass or other suitable plate 21 over which the tape 11 may be carried. If desired, a stationary type cutter 26 may be mounted adjacent the front of this feed plate so that 55 when after being drawn out to the desired extent the length of tape is swung upward against this cutter which may have a serrated edge, if desired, the tape length is severed in the usual way. It is desirable to 60 have a suitable cutter lock, such as 50, arranged in connection with this cutter and this may be conveniently done by forming the cutter lock on the end of the plate 25 on 65 which the serrated edge cutter is formed and by movably mounting these parts as

by pivoting them to the frame so that when the cutter swings up the cutter lock moves down to hold the tape during the severing operation and insure a clean and square cut. The cutter may be provided with the up- 70 standing ears or flanges 24 through which passes the pivot bar 23 mounted in ears or brackets 49 on the frame or feed plate 21.

The moistener of any desired form and construction may be conveniently mounted 75 adjacent the cutter and this moistener is preferably of the belt type, the moistener belt 39 consisting of an endless strip of felt or other suitable porous fibrous material and being preferably mounted on a moistener 80 distributing carrier block 41 depending into the water 29 in the moistening tank and provided with a series of capillary slots or openings so as to raise and distribute this water and more quickly and freely supply the same 85 to the acting surface of the moistener. For this purpose narrow capillary slots may be formed in this block in any desired way and may conveniently be formed in each lateral face thereof, so that these slots 44, 45 are 90 staggered as indicated in Fig. 5 and when the block 41 is made of wood these slots are preferably arranged in a somewhat inclined diagonal position, as shown in Fig. 4, so as to increase the capillary action of the 95 carrier block, the grain of which is for this purpose preferably arranged substantially vertical. These capillary slots greatly increase the water supplying or distributing action of such a moistener and it is also de- 100 sirable to form suitable transverse recesses 47 at intervals along the sides of the block so that the water is certainly and effectively supplied to the inner or rear faces of the moistener at various points along its height 105 so as to be more freely and certainly carried up to its upper acting surface which is preferably formed with a beveled or cut-away edge adjacent the cutter so as to coöperate more readily with the tape. In order to 110 promote the self-cleaning action of the moistener it is preferably made reversible and is removably mounted in the moistener well or space adjacent the front of the moistener tank so that it may be bodily removed by 115 the operator and reversed in position which tends to soften and remove any accumulation of gum that may have adhered to its working face. For this purpose the moistener well at the front of the moistening 120 tank 28 may as indicated in Fig. 2 be formed with the moistener supports 46 projecting from the corners of the ribs 47, 48, so that the moistener block may rest on these moistener supports and be held at the proper 125 height, the moistener being preferably held in alinement longitudinally of the machine as by a moistener spring 43 secured to the front of the tank so as to yieldingly engage the moistener and force it back against the 130

ribs 47. In order to make the moistener thoroughly interchangeable all its corners are formed with somewhat beveled portions 40 an indicated, so that it may be placed in 5 any desired position and still coöperate properly with the cutting and feeding devices, and it is of course understood that the moistening tank is in this way given ample area to hold a relatively large amount of 10 water or other moistening liquid 29 so that considerable tape may be moistened without supplying additional liquid.

In using the machine the tape container is of course put in place and preferably clamped 15 in the position indicated in Figs. 1 and 2 and the tape 11 threaded through the guides and under the cutter so that it can be readily engaged by the operator's finger as indicated in Fig. 1 and drawn or pushed 20 forward over the feed plate until the forward severed end projects a little beyond the moistener 39 so that it can be readily grasped and drawn forward to the desired further extent while being held down in 25 moistening engagement with the capillary moistener. Then when the tape is drawn upward against the cutter to sever a length the severed end is effectively held out of engagement with the moistener and if desired 30 a somewhat upwardly inclined guard 27 which may be stationary may be located beneath the cutter so as to minimize absorption of moisture from the adjacent moistening surface. For this purpose an opening 35 or recess 52 may be formed in the sides of the moistening tank which promotes air circulation and thus minimizes the moistening action on the tape end of the adjacent moistener surface. This guard 27 also preferably 40 has an upwardly deflecting action on the tape end when it is first fed or pushed forward so that it does not undesirably engage the moistener. It is also desirable in order to make more uniform the initial feeding 45 movement of the tape to have a suitable clamping dog or member 20 which may be pivotally mounted about the pin 18 so as to swing downward into contact with the tape on the feed plate 21 and when the operator 50 feeds forward another length of tape his finger naturally engages this clamp and pushes it down sufficiently to hold the tape against backward movement at this time and then when the finger is drawn forward it 55 slips off the clamp and gives a more definite extent of initial feed to the tape before the operator's finger engages the cutter lock or plate 50 which substantially stops this initial feeding movement.

60 This invention has been described in connection with a number of illustrative embodiments, forms, proportions, materials, parts and arrangements, to the details of which disclosure the invention is not of course to be limited, since what is claimed 65

as new and what is desired to be secured by Letters Patent is set forth in the appended claims.

1. In tape moisteners, a frame provided with adjustable side clamps to engage and support a substantially sealed tape roll dispensing container, a moistening tank having a covered rear portion mounted on said frame adjacent said clamps, a guide plate pivotally connected to said frame to coöperate with the forward portion of said tape container and provided with guides for the tape issuing therefrom, a feed plate on the top of said moistening tank, a clamping dog pivotally mounted at the rear portion of said feed plate, a stationary type cutter and a connected cutter lock pivoted to said feed plate adjacent its forward portion, a belt type moistener arranged on a distributing moistener carrier block and having one end extending into said moistening tank so that its upper moistening face projects adjacent said cutter, said carrier block being formed of wood having the grain substantially vertical and provided with a series of staggered inclined capillary slots extending from both front and rear faces thereof and with narrow distributing recesses formed in said front and rear faces.

2. In tape moisteners, a frame provided with adjustable side clamps to engage and support a substantially sealed tape roll dispensing container, a moistening tank mounted on said frame adjacent said clamps, a feed plate on the top of said moistening tank, a stationary type cutter and a connected cutter lock pivoted to said feed plate adjacent its forward portion, a belt type moistener arranged on a distributing moistener carrier block and having one end extending into said moistening tank so that its upper moistening face projects adjacent said cutter, said carrier block being formed of wood having the grain substantially vertical and provided with a series of staggered inclined capillary slots extending from both front and rear faces thereof and with narrow distributing recesses formed in said front and rear faces.

3. In tape moisteners, a frame provided with adjustable side clamps to engage and support a substantially sealed tape roll dispensing container, a moistening tank mounted on said frame adjacent said clamps, a feed plate on the top of said moistening tank, a stationary type cutter secured to said feed plate adjacent its forward portion, a belt type moistener arranged on a distributing moistener carrier block and having one end extending into said moistener tank so that its upper moistening face projects adjacent said cutter, said carrier block being formed of wood having the grain substantially vertical and provided with a series of capillary slots.

4. In tape moisteners, a frame to engage and support a substantially sealed tape roll container, a moistening tank mounted on said frame, a feed plate on the upper rear portion of said moistening tank, a clamping dog pivotally mounted at the rear portion of said feed plate, a stationary type cutter and a connected cutter lock pivotally mounted on said feed plate adjacent its forward portion, a stationary type moistener extending into said moistening tank so that its upper moistening face projects adjacent said cutter.
5. In tape moisteners, a frame to engage and support a tape roll, a moistening tank mounted on said frame, a clamping dog mounted at the rear portion of said feed plate, a stationary type cutter and a connected cutter lock mounted on said feed plate adjacent its forward portion, a stationary type moistener extending into said moistening tank so that its upper moistening face projects adjacent said cutter.
6. In tape moisteners, a substantially closed dispensing container to inclose and revolvably support a roll of gummed tape and allow the withdrawal therefrom of the strip of gummed tape while remaining substantially sealed and preventing undesirable access of moisture to the remaining gummed tape, means comprising laterally adjustable side clamps to support said container, a moistening device mounted adjacent said container with which said strip of gummed tape engages to moisten the same and a cutter to sever the desired lengths of gummed tape from said strip.
7. In tape moisteners, a substantially closed dispensing container to inclose and revolvably support a roll of gummed tape and allow the withdrawal therefrom of the strip of gummed tape while remaining substantially sealed and preventing undesirable access of moisture to the remaining gummed tape, means to support said container, a moistening device mounted adjacent said container with which said strip of gummed tape engages to moisten the same and a cutter to sever the desired lengths of gummed tape from said strip.
8. In tape moisteners, a frame to engage and support a substantially sealed tape roll, a moistening tank mounted on said frame, a clamping dog mounted at the rear portion of said feed plate, a stationary type cutter and a connected cutter lock mounted on said feed plate adjacent its forward portion, a stationary type moistener extending into said moistening tank so that its upper moistening face projects adjacent said cutter.
9. In tape moisteners, a substantially closed dispensing container to inclose a supply of gummed tape and allow the withdrawal therefrom of the strip of gummed
- tape while remaining substantially sealed and preventing undesirable access of moisture to the remaining gummed tape, means to support said container, a moistening device with which said strip of gummed tape engages to moisten the same and a cutter to sever lengths of gummed tape from said strip.
10. In tape moisteners, a substantially closed dispensing container to inclose a supply of gummed tape and provided with a constricted tape aperture to allow the withdrawal therefrom of the strip or gummed tape while the container remains substantially sealed and prevents undesirable access of moisture to the remaining gummed tape, means to support said container, a moistening device mounted adjacent said container with which said strip of gummed tape engages to moisten the same and a cutter to sever the desired lengths of gummed tape from said strip.
11. In tape moisteners, a frame provided with clamping means to engage and support a substantially closed tape roll dispensing container, a moistening tank mounted on said frame, a guide plate pivotally connected to said frame to cooperate with the forward portion of said tape container and provided with guides for the tape issuing therefrom, and adapted to fold adjacent the bottom of said frame for shipping, a stationary type cutter, and a belt type moistener arranged on a distributing moistener carrier block and extending into said moistening tank so that its upper moistening face projects adjacent said cutter.
12. In tape moisteners, a substantially closed dispensing container to inclose a supply of gummed tape and provided with a tape aperture to allow the withdrawal therefrom of the strip of gummed tape while the container remains substantially sealed and prevents undesirable access of moisture to the remaining gummed tape, means to support said container and a cutter to sever lengths of gummed tape from said strip.
13. In tape moisteners, a substantially closed dispensing container to inclose a supply of gummed tape and provided with a tape aperture to allow the withdrawal therefrom of the strip of gummed tape while the container remains substantially sealed and prevents the undesirable access of moisture to the remaining gummed tape, and means to support said container.
14. In tape moisteners, a frame having means to support a tape roll, a moistening tank mounted to cooperate with said tape roll, a feed plate having a stationary upwardly inclined forward portion to act as a moistening guard, a stationary type cutter and connected cutter lock pivoted to said feed plate adjacent its forward portion, a moistener well formed adjacent the for-

- ward portion of said moistening tank and provided with moistener supports at the corners of said well, a moistener spring co-operating with said well to hold the moistener in alinement and a reversible moistener 5 removably mounted in said well and comprising an endless porous moistener belt encircling a distributing moistener carrier block formed with beveled edges adjacent its moistening faces and adapted to rest on 10 said moistener supports within the liquid in said moistening tank, there being a series of inclined staggered capillary slots in said block extending inward from a plurality of faces thereof and a series of transverse distributing recesses in said block coöperating with the inner surfaces of the moistener belt thereon. 15
15. In tape moisteners, a frame having means to support a tape roll, a moistening tank mounted to coöperate with said tape roll, a feed plate having a stationary upwardly inclined forward portion to act as a moistener guard, a stationary type cutter, a moistener well formed in said moistening 20 tank and provided with moistener supports, a moistener spring coöperating with said well to hold the moistener in alinement and a reversible moistener removably mounted 25 in said well and comprising an endless porous moistener belt encircling a distributing moistener carrier block formed with beveled edges adjacent its moistening faces, there being a series of inclined staggered capillary slots in said block extending 30 inward from a plurality of faces thereof and a series of narrow transverse distributing recesses in said block coöperating with said slots and with the inner surfaces of the moistener belt thereon. 35
16. In tape moisteners, a frame having means to support a tape roll, a moistening tank mounted to coöperate with said tape roll, a feed plate, a stationary type cutter, a moistener well formed in said moistening tank and provided with moistener supports and a reversible moistener removably mounted 40 in said well and comprising an endless porous moistener belt encircling a distributing moistener carrier block adapted to rest on said moistener supports within the liquid in said moistening tank, there being a series of staggered capillary slots in said block extending inward from a plurality of faces thereof and a series of transverse distributing recesses in 45 said block coöperating with the inner surfaces of the moistener belt thereon. 50
17. In a tape moisteners, a frame having means to support a tape roll, a moistening tank mounted to coöperate with said tape roll, a feed plate, a stationary type cutter, a moistener well formed in said moistening 55 tank and provided with moistener supports 60
- and a reversible moistener removably mounted in said well and comprising an endless porous moistener belt encircling a distributing moistener carrier block adapted to rest on said moistener supports within the liquid 70 in said moistening tank, there being a series of capillary slots in said block extending inward from a face thereof coöperating with the inner surfaces of the moistener belt thereon. 75
18. In tape moisteners, a frame having means to support a tape roll, a moistening tank mounted to coöperate with said tape roll, a stationary type cutter between said tank and roll, a moistener well formed adjacent the forward portion of said moistening tank, a moistener spring coöperating with said well to hold the moistener in alinement and a reversible moistener removably mounted in said well and comprising an endless porous moistener belt encircling a distributing moistener carrier block formed with beveled edges adjacent its moistening faces, there being a series of inclined staggered capillary slots in said block extending 80 inward from a plurality of faces thereof and a series of narrow transverse distributing recesses in said block coöperating with said slots and with the inner surfaces of the moistener belt thereon. 85
19. In tape moisteners, a frame having means to support a tape roll, a moistening tank mounted to coöperate with said tape roll, a stationary type cutter between said tank and roll, a moistener well formed adjacent the forward portion of said moistening tank, and a reversible moistener removably mounted in said well and comprising a porous moistener belt encircling a distributing moistener carrier block, there being a series of inclined staggered capillary slots in said block extending inward from a plurality of faces thereof and a series of narrow transverse distributing recesses in 90 said block coöperating with said slots and with the inner surfaces of the moistener belt thereon. 95
20. In tape moisteners, a frame having means to support a tape roll, a moistening tank mounted to coöperate with said tape roll, a stationary type cutter between said tank and roll, a moistener well formed adjacent the forward portion of said moistening tank and a reversible moistener removably mounted in said well and comprising a porous moistener belt encircling a distributing moistener carrier block, there being a series of capillary slots in said block extending inward from a plurality of faces thereof and a series of transverse distributing recesses in 100 said block coöperating with said slots and with the inner surfaces of the moistener belt thereon. 105
21. In tape moisteners, a frame having means to support a tape roll, a moistening tank mounted to coöperate with said tape roll, a stationary type cutter between said tank and roll, a moistener well formed adjacent the forward portion of said moistening tank and a reversible moistener removably mounted in said well and comprising a porous moistener belt encircling a distributing moistener carrier block, there being a series of capillary slots in said block extending inward from a plurality of faces thereof and a series of transverse distributing recesses in 110 said block coöperating with said slots and with the inner surfaces of the moistener belt thereon. 115
22. In tape moisteners, a frame having means to support a tape roll, a moistening tank mounted to coöperate with said tape roll, a stationary type cutter between said tank and roll, a moistener well formed adjacent the forward portion of said moistening tank and a reversible moistener removably mounted in said well and comprising a porous moistener belt encircling a distributing moistener carrier block, there being a series of capillary slots in said block extending inward from a plurality of faces thereof and a series of transverse distributing recesses in 120 said block coöperating with said slots and with the inner surfaces of the moistener belt thereon. 125
23. In tape moisteners, a frame having means to support a tape roll, a moistening tank mounted to coöperate with said tape roll, a stationary type cutter between said tank and roll, a moistener well formed adjacent the forward portion of said moistening tank and a reversible moistener removably mounted in said well and comprising a porous moistener belt encircling a distributing moistener carrier block, there being a series of capillary slots in said block extending inward from a plurality of faces thereof and a series of transverse distributing recesses in 130 said block coöperating with said slots and with the inner surfaces of the moistener belt thereon. 135

5 tank mounted to coöperate with said tape roll, a stationary type cutter between said tank and roll, a moistener well formed adjacent the forward portion of said moistening tank, and a reversible moistener 10 removably mounted in said well and comprising a porous moistener belt encircling a distributing moistener carrier block, there being a series of capillary slots in said block 15 extending inward from a face thereof.

22. In tape moisteners, a frame having means to support a supply of gummed tape, a moistening tank mounted to coöperate therewith, a stationary type cutter, a moistener removably mounted in said moistening 20 tank and comprising a porous moistener surface encircling the top and sides of a distributing moistener carrier block formed with beveled edges adjacent its moistening 25 face, there being a series of inclined staggered capillary slots in said block extending inward from a plurality of faces thereof and a series of transverse distributing recesses in said block coöperating with the inner surfaces of the moistener surface thereon.

23. In tape moisteners, a frame having means to support a supply of gummed tape, a moistening tank mounted to coöperate therewith, a stationary type cutter, a moistener removably mounted in said moistening 30 tank and comprising a porous moistener surface encircling the top and sides of a distributing moistener carrier block, there being a series of staggered capillary slots in 35 said block extending inward from a plurality of faces thereof and a series of transverse distributing recesses in said block coöperating with the inner surfaces of the moistener surface thereon.

24. In tape moisteners, a frame having means to support a supply of gummed tape, a moistening tank mounted to coöperate therewith, a moistener removably mounted 40 in said moistening tank and comprising a porous moistener surface encircling the top 45

and sides of a distributing moistener carrier block, there being a series of capillary slots in said block extending inward from a face thereof and a series of transverse distributing recesses in said block coöperating with the inner surface of the moistener surface thereon.

25. In tape moisteners, a frame having means to support a supply of gummed tape, a moistening tank mounted to coöperate therewith, a stationary type cutter, a moistener removably mounted in said moistening tank and comprising a porous moistener surface encircling the top and sides of a distributing moistener carrier block, there being a series of capillary slots in said block and a transverse distributing recess in said block coöperating with the inner surface of the moistener surface thereon.

26. In tape moisteners, a frame provided with means to support a tape roll, a moistening tank, a belt type moistener arranged on a distributing moistener carrier block and having one end extending into said moistening tank so that its upper moistening face projects therefrom, said carrier block being formed of wood having the grain substantially vertical and provided with a series of staggered inclined capillary slots extending from both front and rear faces thereof and with narrow distributing recesses formed in said front and rear faces.

27. In tape moisteners, a frame provided with means to support a tape roll, a moistening tank, a belt type moistener arranged on a distributing moistener carrier block and having one end extending into said moistening tank so that its upper moistening face projects therefrom, said carrier block being formed of wood and provided with a series of capillary slots.
